UNITED STATES PATENT OFFICE.

BRITTON POULSON, OF CHICAGO, ILLINOIS, ASSIGNOR, BY MESNE ASSIGNMENTS, TO
EDWARD W. ROGERS, OF CHICAGO, ILLINOIS.

ROTARY INTERNAL-COMBUSTION ENGINE.

1,210,361.

Specification of Letters Patent. Patented Dec. 26, 1916.

Application filed December 26, 1911. Serial No. 667,995.

To all whom it may concern:

Be it known that I, BRITTON POULSON, a citizen of the United States, residing at Chicago, in the county of Cook and State 5 of Illinois, have invented a new and useful Rotary Internal-Combustion Engine, of which the following is a specification.

My invention relates to rotary engines having radially sliding wings mounted on 10 an eccentric hub within a shell or casing and the objects of my improvements are, first, to provide means whereby the engine may rotate in either direction; second, to afford novel means for moving the wings 15 radially; third, to increase the surface pressure on the power side of the wings; fourth, to arrange means whereby a close fit is assured between the wings and the shell; fifth, to make a very compact, strong and efficient 20 motor and other features to become apparent from the description to follow.

A successful rotary motor or engine is very desirable for use on self-propelled vehicles for the reason that it can be started 25 without cranking and without the necessity of a starter and my invention is designed to fulfil that requirement.

To describe my invention so that others versed in the art to which it pertains can 30 make and use the same I have illustrated the same on the accompanying two sheets of drawings in which:—

Figure 1, is a side elevation of a rotary engine embodying my invention, Fig. 2, is 35 an edge elevation of the same, Fig. 3, is a sectional view taken on line 3—3 of Fig. 2, Fig. 4, is a sectional view taken on line 4—4 of Fig. 1, and Fig. 5 is a section on line 5—5 of Fig. 4, showing the construction of the 40 wings.

Similar reference characters refer to similar parts throughout the several views.

The casing of the engine comprises an inner shell 6 and an outer shell 7 between 45 which is provided a water jacket 8 for cooling the engine by admitting water at 9 and exhausting it at 10. The central portion of 11 of the casing is cylindrical in form and has its open ends closed by the caps 12 and 13 which are secured by means of bolts 14. Within the casing is mounted a circular hub 15 rigid on the shaft 16 which is mounted eccentrically in the casing to rotate in suitable bearings 17 so that the hub

15 will be in constant contact with the inner 55 shell 6 at the top as seen in Figs. 3 and 4.

Mounted to slide in suitable radial slots 18 provided in the hub 15 are the wings 19. The outer free ends of the wings 19 are constantly held in contact with the inner shell 60 6 by means of suitable lugs or pins 20, which are rigidly secured to the edges of the wings 19, extending into the groove 21 formed in the adjacent surfaces of the ends 12 and 13, which groove is made concentric 65 with the bore of the cylinder portion 11. Thus it is clear that when pressure fluid is admitted into the top of the casing to the right of the center line as viewed in Fig. 3, the hub 15 with the wings 19 and shaft 16 70 will rotate, clockwise and if the pressure fluid is admitted into the top of the casing to the left of the center line, the rotation of said parts will be counterclockwise. Since the wings 19 are made to fit snugly 75 in the slots 18 I prefer to provide the air passages 22 near the shaft 16 connecting the inner ends of the slots 18 to avoid the suction and compression of air in the slots 18 due to the movement of the wings 19 in 80 the same.

An inlet port 23 for the admittance of fuel oil and another port for the admittance of air are provided in the portion 11 of the casing at suitable distances either side of 85 the center line at the top as seen in Fig. 3; the ports on the right hand side are used to drive the shaft 16 clockwise and the ports on the left hand side are used to drive the shaft 16 in a counterclockwise direction. 90 The fuel oil, such as gasolene, and the air are injected into the engine casing through the pipes 24 and 25 respectively under pressure and together form a combustible fuel within the shell 6 behind a wing 19, so that 95 if the same is ignited by means of a sparking plug 26 the resulting explosion or burning of the combustible fuel will with great energy force the wing 19 and therefore the shaft 16 around on its axis.

To control the direction of rotating of the shaft 16, suitable valves 27 are provided between the supply pipes 24 and 25 and their respective coöoperating ports leading into the interior of shell 6, which are connected by means of the arms 28 secured to the exposed ends of the valve stems and the connecting rod 29: and are so arranged 100 105

that when the valve 27 on the right hand side as viewed in Figs. 1 and 3 is open the valve 27 on the left hand side is closed and vice versa: and a central position of the said valves and connecting rod will bring both valves to a closed position.

To operate the valves 27, I connect the connecting rod 29 by a link 30 to an operating lever 31 fulcrumed at 32 and provided 10 with the customary spring pressed latch 33 to take into the notched segment 34.

One pole of the electric sparking plug 26 is connected to the casing of the engine and the other pole is electrically connected by 15 wire 35 to the brush 36 which is arranged to consecutively make connection with the contacts 37 rigidly mounted on the shaft 16. The contacts 37 are electrically connected to the annular band 38, against which the 20 contact spring 39 constantly bears. The spring 39 is connected by means of wire 40 to one pole of a source of electric current 41 and the other pole of said source of electric current is connected by wire 42 to the casing 25 of the engine thus completing the electric circuit back to the sparking plug 26. Since the position of the firing chamber for each rotation of the engine *i. e.*, clockwise and counterclockwise, is different and the sparking 30 plugs 26 are located accordingly, each of said sparking plugs is connected to different brushes 36 so as to have the spark properly timed for the operation of the engine, and since only one brush 36 is necessary at a time I preferably mount both 35 brushes on a beam 43 pivotally mounted at 44 to the cap 12 and arrange one branch 45 of said beam with an offset which lies between two extensions 46 provided on connecting rod 29. These parts are so arranged 40 that when the operating lever 31 is moved to open the valve 27 which causes the shaft 16 to rotate clockwise the brush 36 which is connected to plug 26 which coöperates with 45 said valve will be brought into electric connection with the contacts 37 and the other brush 36 will be moved to a position out of contact with said contacts 37.

The explosions or burning of the combustible charge as previously referred to takes 50 place within the inner shell back of a wing 19 and forces said wing around in its path until said wing reaches a position opposite the exhaust opening 47 at the bottom of the 55 casing through which the remaining force of the explosion will pass.

The inner wall of the inner shell is extended outward for some distance at the intakes 23 to form an explosion chamber 48 50 and the hub 15 has a depression 49 immediately in front of each wing 19 so as to increase the capacity of the explosion chamber and also expose a larger area of each 65 wing 19 when the shaft 16 is rotating clockwise as viewed in Fig. 3.

To have the edges of the wings 19 fit more closely to the inner shell 6 and thus prevent leakage at their junction I provide a groove in the three edges of each wing 19 into which are fitted the rectangular bars 51. 70 The bottom of each groove 50 is connected by suitable holes 52 with one side of the wings so that as the shaft 16 is driven clockwise the fluid pressure bearing against the side of the wing will enter the holes 52 and 75 force the bars 51 tightly against the inner shell 6, see Fig. 5.

Since the pressure in the explosion chamber 48 at the time of ignition is considerably greater than the pressure in the supply 80 pipes 24 and 25 I provide the check valves 53 in the supply pipes adjacent the valves 27.

In operation, presuming that the engine is at a standstill and it is desired to have it run forward or clockwise as viewed in 85 Fig. 3, the operating lever 31 is moved to the right as viewed in Fig. 1; thus opening the right hand valve 27 and moving its companion brush 36 into connection with the contacts 37. First, the motor or wings will 90 be driven around by reason of the pressure from the fuel supply source entering the explosion chamber, and as soon as ignition takes place the engine will be working at its full capacity providing the valve 27 is 95 retained in its wide open position. Any desired speed may be attained by throttling at the valve 27: provision being made for this by providing lost motion between the extensions 46 on connecting rod 29 and the branch 100 45 of beam 43. A spring 54 being connected to the beam 43 to constantly hold against the contacts 37 whichever brush 36 has been moved into connection with said contacts. There being four wings 19, there will be 105 four explosions for every revolution of shaft 16.

It will be understood that changes may be made in the form and arrangements of the parts which would be within the meaning of shop practice without departing from 110 the scope of my invention.

Having thus fully described my invention what I claim as new and desire to secure by Letters Patent of the United States is:— 115

1. In a device of the class described, a suitable frame provided with an interior circular chamber, a hub rotatably mounted within said circular chamber arranged to engage the top of said chamber and provided with a plurality of radial slots, a suitable wing fitted to slide in each of said slots, said frame provided with an exhaust port leading from the lower side of said chamber to form an explosion chamber on each side 120 of the hub, and with valved intake ports leading to each of said explosion chambers, a spark plug provided in each explosion chamber, a rocking beam pivotally mounted at its center and provided with an electric 125 130

contact brush at each free end, a rotatable electric contact member to coöperate with said electric contacts on the beam and means whereby the valves on the intake ports are 5 operated simultaneously with the rocking of the beam whereby the engine can be made to run in either direction.

2. In a device of the class described, a suitable frame provided with an interior circular chamber, a hub rotatably mounted within said circular chamber arranged to engage the top of said chamber and provided with a plurality of radial slots, a suitable wing fitted to slide in each of said slots, communicating passages connecting the bottom 10 of said slots so that the air in lower ends of the slots is free to pass from one slot to an-

other as the wings slide in and out of said slots, a groove in the edge of each wing, a metal packing bar fitted into each of said 20 grooves and passageways leading from the bottoms of said grooves to one side of the wing so that pressure fluid applied to one side of said wing will force the packing bars in the grooves outward against the surface of the circular chamber. 25

In testimony whereof I have signed my name to this specification, in presence of the subscribing witnesses, this 21st day of December, 1911, at Chicago, Illinois.

BRITTON POULSON.
